UNITED STATES PATENT OFFICE.

CHARLES E. BURROUGHS, OF CINCINNATI, OHIO.

FLYING-MACHINE.

1,320,839.

Specification of Letters Patent.

Patented Nov. 4, 1919.

Application filed April 30, 1917. Serial No. 165,462.

To all whom it may concern:

Be it known that I, CHARLES E. BURROUGHS, a citizen of the United States of America, and a resident of Cincinnati, in 5 the county of Hamilton and State of Ohio, have invented a certain new and useful Improvement in Flying-Machines, of which the following is a specification.

This invention relates to flying-machines 10 having lifting-propellers, forwarding-propellers and stabilizing-planes together with suitable power and controlling devices, whereby the machine may ascend or descend at variable speeds and in the direction required, the operator being enabled to handle said machine so that it can be kept in motion, advanced forwardly, practically floated or sustained at a stand-still in mid-air, and advanced in a straight line or in a slanting 15 line, or in a circular line, or piloted downwardly in a straight or other path and landed at the desired point to suit the purpose or objective of the operator.

The details of structure as well as the 20 *modus operandi* will be fully hereinafter referred to in connection with the accompanying drawings, in which,—

Figure 1 is a longitudinal elevation, taken on a small scale, showing the machine in its 25 flight upwardly and at an angle forwardly in the direction of the adjacent arrow at its fore end; Fig. 2, a plan view of Fig. 1; Fig. 3, a transverse section taken through the center of the machine, on the dotted-line 30 x, x , of Fig. 1; Fig. 4, a rear-end view of the machine, but on a slightly larger scale than that of the three previous views; Fig. 45 5, a fore-end elevation of the machine taken on the same scale as that of Fig. 4; Fig. 6, a fragmentary side-elevation showing the 40 chain-driving and lever-control devices for the side stabilizing-planes; Fig. 7, a fragmentary elevation of the lever, chain and wire control devices for the rudder of the machine; and Fig. 8, a fragmentary elevation 45 of the engine, lever, chain and friction-drive controlling devices used in lifting and propelling the machine.

The frame of the machine is a skeleton 50 one, both light and strong, and composed of a lower tier made up of longitudinal, vertical and inclined rods, truss-fashion, and is provided with a base or platform 1, at the center of which platform is located an engine 2 for driving the various parts of the 55 machine that are to be driven and to form

the motive power thereof. The engine is under control of a set of levers convenient to the operator or pilot who is intended to stand close to said engine, and at the middle 60 of the machine as usual.

It is intended that the base or platform shall be maintained in a level or horizontal position as much and as closely as possible, all the parts being arranged so that there is 65 not a material overload or deflection at any point therein.

The said lower tier of rods is surmounted by an upper tier of duly arranged and connected longitudinal as well as vertical rods 70 to make up a supporting-frame 3 for the lifting and propelling devices that I will now proceed to describe.

The lifting devices are preferably composed of a double or superposed series of 75 horizontal propellers that are mounted on vertical shafts, the lower series of shafts 4 being short ones and surmounted by propellers 5, and alternated by long shafts 6, the latter being surmounted by propellers 7, the 80 propellers 5 and 7 being thereby, preferably but not essentially, arranged out of vertical alinement so that they succeed in gathering all the air possible for the ascent of the machine. The propellers 5 and 7 are each 85 made up of light but strong canvas buckets that are somewhat pliable or flexible and are adapted to scoop to the fullest extent the air within reach and to develop the maximum of impingement that is not ordinarily 90 possible with the tractor-blades heretofore in use in this class of flying-machines. In Fig. 1 I have shown a greater number of bucket-propellers 5 in the lower series than in the upper series 7, the number in each 95 series being dependent upon the size of machine.

The lower ends of the shafts 4 and 6 are provided with sprocket-wheels 4^a and 6^a, respectively, and, over which sprocket-wheels 100 an ordinary drive-chain 6^b is engaged for rotating said shafts, said chain being made to alternate in connection with the series of sprocket-wheels so that the lower series of bucket-propellers 5 is driven in a direction 105 the reverse of that of the series of bucket-propellers 7 and so as to maintain the equilibrium of the machine as much as possible, especially at its upper part and to prevent its turning, what is termed, "tur- 110 tle." Said chain 6^b is driven by a vertical shaft 8 that is duly geared to the driving

engine 2 located at the center of the machine and under control of a suitable lever 9, as shown in Fig. 1, or by means of a vertical chain 9^a and miter-gears 9^b, as best shown in Fig. 6.

A rear propeller 10 is provided at the tail end of the horizontal shaft 11, the latter, in turn, being driven by a sprocket-chain 12 that, also, in turn, is driven by a shaft 13, the latter being close to the floor or platform 1 of the machine, as best shown in Fig. 1, and preferably connected with the engine by means of a friction-drive composed of the disks 12^a and 12^b, as shown in Fig. 8, so that the said rear-propeller 10 can be driven at variable speeds and under due control of the pilot through lever 12^c. The said propeller 10 is made up of the same canvas buckets as that referred to in connection with the lifting-buckets of the propellers 5 and 7 and in the same form for the better impingement on the air for the forwarding movement or action of the machine. The chain 9^a (Fig. 8) engages at its lower bight with a sprocket-wheel 9^c keyed to a shaft 9^d, a small friction-wheel 9^e being mounted on said latter shaft and variably engaging the face of disk 9^f. Clutches 10^a and 11^a are mounted on the shaft 13 for engagement with the disks 9^e and 12^a through the instrumentality or medium of the actuating levers 9 and 12^b.

A rudder 14 is provided at the fore end of the machine and under due control of the pilot by means of the usual rods 14^a, chain 14^b, gear 14^c and lever 14^d, as best shown in Fig. 7, and that center at his position beneath the protector-hood 15 that is duly supported above the engine and the controlling levers, the latter as shown best in Fig. 1.

A series of three planes is provided at the opposite sides of the machine; they being mounted in pairs at the opposite ends of horizontal shafts distributed along the frame-work, so that one shaft shall be at the center of the machine directly above the protector-hood 15 just below the plane of the lower edges of the lifting-propellers 5 and the other two shafts being at the opposite ends of the frame-work, one being to the rear of the rudder and the other to the fore of the propeller 10, all as best shown in Fig. 1, but also well shown in Fig. 2. The opposite end-planes are designated as 16 and 55 the middle-planes as 17, the said opposite end-planes being narrower than those 17, it being intended thereby to obtain the best stabilizing effect at the main or middle portion of the machine where the most weight 60 thereof is present. These stabilizing-planes are actuated or placed under control of the pilot through the medium of sprocket chains 19, 20 and 21 and wheels 22, 23, 24 and 25 that lead to a lever 18 convenient to his 65 position. These stabilizing-planes further

form wings or the like that may be angled at an inclination, as shown in Fig. 1, to suit the degree of forward-movement upwardly in order to attain the desired altitude, the greater the degree of inclination of such planes toward a vertical position thereof being utilized for a more direct perpendicular ascent and the lesser the degree, toward the horizontal position of such planes, being for a less direct vertical ascent but for a gradual ascent, as well as descent of the machine. In descending, these planes serve as braking or retarding means for regulating such descent and especially when approaching a landing of the machine. In order to have a speedy descent of the machine it is evident that said planes must be arranged in a perpendicular position so as not to retard the downward-movement thereof, and the lifting-propellers 5 and 7 are then used, under 80 due control of the pilot, to make such descent just as speedy as he deems fit and in proportion to the speed at which the engine 2 is run.

The stabilizing-planes are also used in connection with duly balancing the machine and keeping its platform or base 1 as nearly level as possible and especially in making circular movements while in flight and in reversing the onward passage of the machine.

I claim:

1. In a flying-machine, a base or platform, a driving-engine, a rear advancing-propeller operatively-connected with the said engine, a fore steering-rudder, superposed single rows of horizontal lifting-propellers provided along the longitudinal center of the machine, and, also, operatively-connected with the said engine, adjustable stabilizer blades or planes provided along the opposite sides of the said superposed lifting-propellers and adjacent the bases thereof, and means comprising hand-levers and transmitting chains or rods for independently controlling the said engine and the said lifting-propellers, side blades or planes, advancing-propeller and steering-rudder.

2. In a flying-machine, a base or platform, a driving-engine mounted on said platform, a rear driving-propeller adapted to be actuated by said engine, a fore-rudder, a horizontal row of horizontal lifting-propellers mounted along the longitudinal center of the machine on vertical shafts operatively-connected with the said engine, a superposed horizontal row of horizontal lifting-propellers also mounted along the longitudinal center of the machine on vertical shafts alternating with the shafts of said lower row of lifting-propellers, means connected with the said engine for driving the said several rows of lifting-propellers in opposite directions, rocker, horizontal, stabilizer blades or planes mounted successively on

horizontal shafts that bear in the frame of the machine and arranged at the opposite sides of the machine adjacent the base of the lower row of lifting-propellers, and means comprising hand-levers and connecting rods or chains for independently controlling the said engine and the said propelling, lifting, steering and stabilizing devices.

10 3. In a flying-machine, a base or platform, a driving-engine mounted on the said platform, skeleton frame-work, an advancing-propeller mounted on a shaft bearing in the said frame-work, a steering-rudder at the 15 fore end of the machine, a pair of superposed rows of horizontal lifting-propellers mount-

ed on vertical shafts that alternate each other so that the upper row of said lifting-propellers shall be out of vertical alinement with the lower row, means to actuate the 20 said superposed rows of lifting-propellers in opposite directions, stabilizing blades or planes swung on horizontal shafts at the opposite sides of the frame-work, the middle pair of blades or planes being wider than 25 those at the opposite ends of the machine, and means comprising hand-levers and connecting rods or chains for independently controlling the said engine, advancing-propeller, steering-rudder, lifting-propellers and 30 stabilizing blades or planes.

CHARLES E. BURROUGHS.
